UNITED STATES PATENT OFFICE.

JAMES W. THOMAS, OF BALTIMORE, MARYLAND, ASSIGNOR TO JOHN J. MORGAN, OF BALTIMORE, MARYLAND.

PNEUMATIC TRACK-SANDER.

SPECIFICATION forming part of Letters Patent No. 747,308, dated December 15, 1903.

Application filed September 17, 1903. Serial No. 173,522. (No model.)

To all whom it may concern:

Be it known that I, JAMES W. THOMAS, a citizen of the United States, residing at Baltimore, in the State of Maryland, have invented 5 certain new and useful Improvements in Pneumatic Track-Sanders, of which the following is a specification.

This invention relates to improvements in pneumatic track-sanders.

10 Among the objects of the invention are to provide means whereby when the sand-reservoir is in communication with the forward sand-discharge pipe communication with the rear sand-discharge pipe will be cut off, or vice versa, to provide means for controlling 15 the flow of air and sand to the forward and rear sand-discharge pipes, and to provide means to prevent the sand from becoming packed in the sand-valve.

20 In the present track-sanders now in general use the sand-valve is in communication with both the rear and forward sand-discharge pipes at the same time, which has been found to be objectionable, as it has frequently happened that when the air is turned on to force 25 the sand through the forward sand-discharge pipe the sand has become packed or hardened from being damp and subsequently dried and cuts off communication to the said 30 forward sand-discharge pipe, causing the sand flowing from the sand-reservoir to back up in the sand-valve and be discharged through the rear sand-discharge pipe, or vice versa. In my present invention I have overcome 35 this objection by providing means whereby only one of the sand-discharge pipes is in communication with the sand-valve at one time and also by providing means to prevent the sand from being packed or hardened 40 in the sand-valve.

Other features of the invention will be fully set forth in the following specification, and pointed out in the claims.

In the accompanying drawings, Figure 1 is 45 a side elevation of a locomotive, partly broken away, having my improved sander applied thereto. Fig. 2 is a vertical sectional view of the sand-valve, showing the connections thereto. Fig. 3 is an inverted plan view of Fig. 2, partly broken away. Fig. 4 is a cross-section on the line A B of Fig. 2. Fig. 5 is

a detailed side elevation of the inner sleeve of the sand-valve, showing the ports for controlling communication of the air-pipes and sand-reservoir with the sand-discharge pipes. 55 Fig. 6 is an inverted plan view showing the connection between the sanders on opposite sides of the locomotive, the connecting-rod being broken away.

Similar reference-numerals designate like 60 parts throughout the several views.

Referring to the accompanying drawings, forming part of this specification, 1 designates the sand-valve casing, the upper end of which is opened and screw-threaded on its 65 inner surface to receive the threaded end of the pipe 2, which latter is connected at the opposite end to the sand-reservoir. The sand gravitates from the sand-reservoir 3 through the pipe 2 to the sand-valve. 70

The valve-casing 1 is provided with screw-threaded apertures 4 and 5, into which are screwed the air-jet nozzles 6 and 7, respectively, the said nozzles projecting into the sand-valve. These air-jet nozzles 6 and 7 75 are screw-threaded on their outer ends, to which are screwed the forward and rear air-pipes 8 and 9, respectively. These air-pipes 8 and 9 are connected to the air-pipe 10, leading to the air-reservoir, and are provided with 80 valves 11 and 12, respectively, to control the flow of air to the sand-valve. The said valve-casing 1 is also provided with the screw-threaded apertures 13 and 14, into which are screwed the forward and rear sand-discharge 85 pipes 15 and 16, respectively. The said sand-discharge pipes extend down close to the rail.

Within the valve-casing 1 is fitted a sleeve 17, open at its upper end and impinging against the shoulder 18 on the valve-casing. 90 The lower end of the said sleeve 17 is closed and rests upon the cap 31, which latter is screw-threaded upon the lower end of the casing 1. This sleeve 17 has an integral stem 19, which projects through the aperture 20 95 in the cap 31 and is provided with a square head 21. The sleeve 17 is provided with two elongated apertures 22 and 23, through which the air-jet nozzles 6 and 7, respectively, project and which permit of the said sleeve being reciprocated; also two ports 24 and 25, adapted to register with the sand-discharge 100

5 pipes 15 and 16, respectively, but arranged in such a position that when the port 24 is in communication with the sand-discharge pipe 15 the port 25 will be thrown out of communication with the sand-discharge pipe 16, or vice versa.

Upon the square head 21 of the stem 19 is fitted a bell-crank lever 26, one arm of which is connected to the engineer's lever 27 by the 10 rod 28. The other arm of the said bell-crank lever 26 is connected by a rod 29 to the lever 30 of the sander on the opposite side of the locomotive, the sanders on opposite sides of the locomotive being operated simultaneously 15 by the lever 27.

It will be seen that by turning the sleeve 17 for the purpose of changing from the forward to the rear sander, or vice versa, the sand will be prevented from packing in the 20 sand-valve, or should the said sleeve be left standing in one position for any length of time and the sand become packed the engineer can loosen the said sand by simply moving the lever 27 back and forth several 25 times.

While I have shown and described my invention as applied to a steam-locomotive, it is obvious the same may be employed upon electric cars, &c., whenever air-pressure can be 30 obtained.

Having thus described my invention, what I claim is—

1. A pneumatic track-sander comprising a casing having an opening for communication 35 with the sand-reservoir, an opening for communication with the forward sand-discharge pipe, an opening for communication with the rear sand-discharge pipe, and two openings for communication with the two air-delivery 40 pipes; a sleeve fitted in the said casing and having two ports adapted to register with the sand-discharge pipes; and means for rotating said sleeve.

2. A pneumatic track-sander comprising a 45 casing having an opening for connection with the sand-reservoir, an opening for connection with the forward sand-discharge pipe, an opening for connection with the rear sand-discharge pipe; two air-jet nozzles projecting 50 into the said casing, one opposite each sand-discharge pipe; a sleeve fitted in the said casing and having two ports adapted to register with the sand-discharge pipes, and two elongated apertures through which the air-jet 55 nozzles project; and means for rotating said sleeve.

3. A pneumatic track-sander comprising a 60 casing having an opening for communication with the sand-reservoir, an opening for connection with the forward sand-discharge pipe, an opening for connection with the rear sand-discharge pipe, and two openings for connection 65 with the two air-delivery pipes; a sleeve

fitted in the said casing and having two ports adapted to register with the sand-discharge 65 pipes, and a stem projecting through said casing; and means attached to said stem for rotating said sleeve.

4. A pneumatic track-sander comprising a 70 casing having an opening for connection with the sand-reservoir, an opening for connection with the forward sand-discharge pipe, an opening for connection with the rear sand-discharge pipe, and two openings for the air-jet nozzles; a sleeve fitted within the said 75 casing and having two ports adapted to register with the sand-discharge pipes, and two elongated apertures through which the air-jet nozzles project; two air-jet nozzles secured in the casing and projecting into the said 80 sleeve; and means for rotating said sleeve.

5. A pneumatic track-sander comprising a 85 casing having an opening for connection with the sand-reservoir, an opening for connection with the forward sand-discharge pipe, an opening for connection with the rear sand-discharge pipe, and two openings for connection with the air-delivery pipes; a sleeve 90 fitted within the said casing and having two ports adapted to register with the sand-discharge pipes, a stem integral therewith and projecting through the casing; a bell-crank lever fitted upon the said stem; a rod connecting one arm of said bell-crank lever with the sander on the opposite side of the locomotive; and means connected to the other arm for rotating said sleeve.

6. A pneumatic track-sander comprising a 95 casing having an opening for connection with the sand-reservoir, two openings for connection with the sand-discharge pipes, and two openings for the air-jet nozzles; two air-jet nozzles projecting into said casing; a cap 100 removably secured to the lower end of the said casing and having an aperture therein; a sleeve fitted within the said casing and having an integral stem projecting through the aperture in said cap, two ports adapted to register with the sand-discharge pipes, said ports being so arranged that when one is in 105 communication with its respective sand-discharge pipe the other will be thrown out of communication, and two elongated apertures through which the air-jet nozzles project; and means connected to the said stem for rotating the sleeve, whereby the sand-reservoir 110 can be brought into communication with either the forward or rear sand-discharge pipes.

In testimony whereof I affix my signature 115 in the presence of two witnesses.

JAMES W. THOMAS.
